UNITED STATES PATENT OFFICE.

ROBERT E. GAY, OF ATTLEBORO, MASSACHUSETTS, ASSIGNOR TO BATES AND BACON,
OF ATTLEBORO, MASSACHUSETTS, A FIRM.

CIGAR-CUTTER.

1,177,098.

Specification of Letters Patent. Patented Mar. 28, 1916.

Application filed April 30, 1915. Serial No. 24,852.

To all whom it may concern:

Be it known that I, ROBERT E. GAY, a citizen of the United States, residing at Attleboro, in the county of Bristol and 5 State of Massachusetts, have invented certain new and useful Improvements in Cigar-Cutters, of which the following is a specification.

My invention relates to cigar cutters, and 10 has for its essential objects the provision of means whereby the end of a cigar may be severed with greater speed and with less manual exertion and by a more natural movement by the operator than has heretofore been possible.

A further object is to attain a maximum of shearing radius or power in the jaws combined with a minimum of space.

Further objects are adaptability to ornamentation, portability, simplicity and inexpensiveness of construction.

Other advantages will be apparent to those skilled in the art in connection with the description of the structure.

To the above ends essentially my invention consists in such parts and combinations of parts as fall within the scope of the appended claim.

In the accompanying drawings which 30 form a part of this specification, Figures 1, 2 and 3 are front, side and plan elevations respectively of my cigar cutter, Figs. 4, and 5 sections on line $x-x$ of Fig. 2 showing respectively the parts in open and closed positions, and omitting the attaching ring, and Fig. 6, an enlarged section on line $y-y$ of Fig. 5.

Like reference characters indicate like parts throughout the views.

In detail my cigar cutter consists of a body A comprising in the present instance side plates α alike in all respects. The plates are preferably retracted near their upper ends as at α' whence they gradually increase 45 in breadth to their top portions α^2 , said top portions being slightly of less breadth than the oval body portion α^3 . These plates are provided in their retracted portions with beveled openings B in alinement with each other. In the lower portions of the plates are perforations c which receive a tubular rivet D whose ends d are headed over 50 against the outer faces of the body plates α . Surrounding the rivet D is a spacing sleeve

E whose ends abut against the inner faces 55 of the plates α , and cooperate with the rivet to hold the body plates parallel with each other at one end. The end portions α^3 of the plates are connected by spaced pins f fixed thereto by solder or otherwise, and in horizontal alinement with each other near the lateral margins of the plates.

Two cutting or shearing members G of substantially similar construction comprise arms g outwardly curved from each other 65 intermediate their length, and provided at their lower ends with openings g' to loosely receive the member E upon which the arms rotate. Adjacent the perforations the arms have recesses g² in their faces to permit 70 overlapping of the perforated portions of the arms in order to bring the arms into approximately the same plane with each other. Near their upper portions the arms g are expanded outwardly to form broad 75 rounded finger bearing shoulder portions g³, merging into and forming portions of inwardly directed flat blades H of less thickness than the shoulder portions adapted to overlap and slide upon each other. 80 The blades are provided with arcuate beveled cutting edges h upon their adjacent inner margins, and upon the tops of the blades adjacent the beveled edges are vertical lugs i adapted to contact with the stop 85 pins f. Upon intermediate portions of the arms g are flat projections J which support and are inclosed by a flat helical spring K whose ends abut against the compressible arms, and which hold the latter distended 90 in their normal open position.

A cigar end may be placed in the opening formed by the holes B, and the thumb and finger of the operator bearing against the shoulders g³ pinch the blades H together so 95 that the cutting edges h pass each other and by a shearing action sever the cigar end. The described movement is limited to the necessary degree by the contact of the forward edges of the lugs i with their opposite 100 stop pins f.

When the manual pressure upon the blades H is discontinued the arms are forced back by the spring K to original position, excessive travel in this direction being prevented by the contact of the rear edges of the projections with the pins f. This structure is adapted for attachment to a chain,

and for this purpose a ring L passes through the member D and through this may pass the end link of a chain.

What I claim is:—

- 5 A pair of oblong plates having alined cigar-tip receiving openings and held in spaced relation by rivets, one rivet being centrally arranged at one end of said plates and a pair of spaced rivets at the other end
- 10 of said plates, and normally-separated arms pivotally mounted on the central rivet, carrying cutting blades and having operat-

ing portions normally projecting beyond the side lines of the plates, said arms carrying lugs arranged to contact with the spaced 15 rivets limiting the movement of the arms in each direction.

In testimony whereof I have affixed my signature in presence of two witnesses.

ROBERT E. GAY.
